LAY FOR NARROW WARE LOOMS

Elbridge R. Holmes, Worcester, and Paul L. Saftord, Shrewsbury, Mass., assignors to Crompton & Knowles Loom Works, Worcester, Mass., a corporation of Massachusetts

Application February 6, 1950, Serial No. 142,562

7 Claims. (Cl. 139—136)

1

This invention relates to improvements in lays for narrow ware looms and it is the general object of the invention to provide a simple and cheap means for protecting the rack rod on looms the lays of which are made more particularly of a light-weight metal.

The lays of narrow ware looms are frequently made to locate the shuttle blocks at different distances apart to permit the weaving of webs of different widths. Thus, when the web being woven is quite narrow the shuttle blocks are relatively close together, but when the webs are much wider the blocks are spread apart a greater distance. The blocks carry pinions which mesh with the shuttles and also with a rack rod which reciprocates along the lay. The teeth of the rack rod ordinarily face upwardly and are likely to collect dust or lint unless adequately protected and covered.

When narrow ware lays are made of a light-weight metal such as aluminum or magnesium or their alloys it is a matter of practical difficulty to provide suitable coverage or protection for the parts of the rack rod which extend between the shuttle blocks, particularly when the blocks are to be close together under some conditions and farther apart under other conditions. It is an important object of the present invention to provide cover plates for the lay extending over the rack rod between the shuttle blocks and held in position by spring clips or the like which can be readily snapped into position without requiring the use of screws, etc., extending into the lay.

It is a further object of the invention to provide a metal lay beam with longitudinally extending beads or grooves to receive the arms or fingers of spring clips which hold the cover plates in position.

In order that the spring clip may have adequate resilience one of its vertical arms is made relatively long to fit into a groove or under a bead located on an appreciable distance below the top of a lay beam. Since these clips are in alignment with the reed dents located at the back of the lay it is preferable that the long arms be at the front of the lay so that there will be a minimum of interference between the clips and the reeds.

When the shuttle blocks are of different spacing it is necessary to employ cover plates of different widths, but in order that the manner of holding in position may be efficient and cheap it is a further object of the invention to make the clips of a uniform width less than the nar-

2

rowest of the cover plates so that only one set of spring clips will be needed for a lay to be used with cover plates of various widths.

With these and other objects in view which will appear as the description proceeds, the invention resides in the combination and arrangement of parts hereinafter described and set forth.

In the accompanying drawings, wherein a convenient embodiment of the invention is set forth,

Fig. 1 is a front elevation of one end of the lay of a narrow ware loom having the invention applied thereto,

Fig. 2 is an enlarged transverse vertical section on line 2—2, Fig. 1,

Fig. 3 is a perspective view of a protecting cover plate,

Fig. 4 is a perspective view of the resilient clip which fits over the plate, and

Figs. 5 and 6 are diagrammatic views showing two spacings of shuttle blocks on two different lays or as the blocks may be arranged at different times on the same lay, and indicating cover plates of different widths.

Referring particularly to Fig. 1, the lay beam 10 is mounted on swords one of which is indicated at 11 and reciprocates backwardly and forwardly in usual manner. The beam has an upwardly opening slot 12 defined between front and back walls 13 and 14, respectively. Located within the slot between the walls is a rack rod 15 which may be reciprocated by means of a cable 16 trained over a sheave 17 rotatable on the lay beam.

A plurality of shuttle blocks 20 are spaced along the lay and are held in position by block supports or backs 21 secured as at 22 to the back of the beam. Each block has rotatable therein a pinion 23 meshing with the rack rod 15 and also with a shuttle S. The blocks are provided with curved guide grooves 24 along which the shuttles move. Each shuttle passes from one block across a warp space 25 to the adjacent block in one direction when the rack rod moves in one direction with respect to the lay and has a return movement across the space 25 when the rack rod moves in the opposite direction. Except as noted hereinafter the foregoing is of usual construction and operates in the ordinary manner.

The beam 10 has front and back upper surfaces 30 and 31, respectively, extending along the tops of the walls 13 and 14. Resting on these surfaces between the shuttle blocks are cover plates 32 one of which is shown in Fig. 3. The 55 cover plate may be made of thin material, pref-

erably wood, and is of a sufficient width to cover the rack rod between adjacent blocks 29. The blocks extend over and cover the rack rod between the plates 32.

The front wall 13 is provided with a groove 35 below a bead 36 and the rear wall 14 has a second groove 37 below a bead 38. The grooves and beads run lengthwise of the beam are preferably parallel to their respective top surfaces 39 and 31.

A resilient clip 40 is provided for each of the cover plates, each clip including a flat body 41; a rear down-turned edge forming a short arm or finger 42 having a rib 43 to enter the rear groove 37 under the bead 38, and a forward relatively long arm or finger 45 having a bend or crimp 46 to enter the forward groove 35 under bead 36. The body 40 preferably extends forwardly from the front wall 13 a slight amount as indicated for instance at 47 in Fig. 2, and the front and back arms 45 and 42 are of such length that when they are engaged in their respective grooves, or under their respective beads, the body 40 presses down on the cover plate thereunder and holds the plate firmly in position on the lay. The clip 40 is preferably made of a resilient material, such as spring or sheet steel, and can be readily detached from the beam when it is desired to remove the cover plate by insertion of a suitable tool, as a screw driver, into groove 35 and under crimp 46.

Fig. 5 shows shuttle blocks 20A arranged in close order so that the cover plates 32A will be quite narrow. Fig. 6, on the other hand, shows shuttle blocks 20B spaced apart by a considerable distance and requiring a wider cover plate 32B. It will be noted, however, that in both Figs. 5 and 6 the spring clips 40 are of the same width.

In the construction of narrow ware looms it is customary to mount reeds between the shuttle blocks. These reeds are designated at R and as shown in Fig. 2, where one of the reeds is set forth, the bottom reed rail 50 rests on an angle support 51 secured as at 52 to the lay beam 10. The rear short arm 42 of the clip is located a short distance above the bottom rail 50 forward of the reed dents 53 and does not interfere with the reed. It is because of the location of the reed that it is preferable to have the long arm 45 on the front part of the lay.

The lay beams may be extruded which permits the grooves to be formed at the time that the beam is made. There may be slight variations in the width of the beam throughout its length and one of the reasons for the long arms 45 is to take this variation into account. When the clip is in its normal relaxed form the distance between the bottoms of the arms 42 and 45 will be slightly less than the minimum width of the beam between grooves 35 and 37 which is likely to be encountered. In this way the clips are always under some resilient stress tending to hold them in place.

From the foregoing it will be seen that the invention sets forth simple means by which the cover plates 32 may be detachably secured to the top of the lay beam over the rack rod to protect the latter from dust and lint. The plate is not secured directly to the lay beam, but is held in position by a clip which has resilient arms entering grooves running lengthwise of the lay beam, or caught under beads on the beam. The clips are of a relatively narrow width and can be used with cover plates of various widths. Since the grooves run lengthwise of the beam the

clips can be secured at any desired points along the length of the beam depending upon the width of the spaces between the shuttle blocks. Also, the forward depending arm of each clip is preferably sufficiently long to provide adequate resilience and extends forwardly from the top of the lay beam to accommodate slight variations in the width of the beam.

Having thus described the invention it will be seen that changes and modifications of the foregoing specific disclosure may be made without departing from the spirit and scope of the invention.

What is claimed as new is:

1. In a lay for a narrow ware loom, a lay beam having a slot therein containing a rack rod, spaced shuttle blocks on the beam extending over the slot, a cover plate on the beam between the blocks and over the slot, and a resilient clip extending over the cover plate resiliently engaging the beam and holding the cover plate in position on the beam.

2. In a lay for a narrow ware loom, a lay beam having a slot therein containing a rack rod, spaced shuttle blocks on the beam extending over the slot, a cover plate on the beam between the blocks and over the slot, and a resilient clip extending over the cover plate resiliently engaging the beam at points below the plate and holding the latter in position on the beam.

3. In a lay for a narrow ware loom, a lay beam having a slot therein containing a rack rod, spaced shuttle blocks on the beam extending over the slot, a cover plate lying on the beam between the shuttle blocks and over the slot, and resilient clip means extending transversely of the beam over and engaging the plate between the shuttle blocks and having downbent ends resiliently engaging the beam and holding the plate and clip down on the beam.

4. In a lay for a narrow ware loom, a lay beam having a slot therein containing a rack rod, transversely spaced beads on the beam running lengthwise thereof below the top of the beam, spaced shuttle blocks on the beam extending over the slot, a cover plate lying on the top of the beam between the shuttle blocks and over the slot, and resilient clip means transverse of the beam extending over and engaging the plate and having downbent ends resiliently engaging said beads and holding the plate and clip down on the beam.

5. In a lay for a narrow ware loom, a lay beam having a slot therein containing a rack rod, spaced shuttle blocks secured to the beam, a cover plate extending over the slot between said shuttle blocks, beads on the beam, one at the front and the other at the back of the beam, and a resilient clip extending over the plate and engaging the beads and holding the cover plate in position on the beam.

6. In a lay for a narrow ware loom, a lay beam having a slot therein containing a rack rod, spaced shuttle blocks secured to the beam, a cover plate extending over the slot between said shuttle blocks, a resilient clip extending over the plate transversely of the lay and having an arm extending down along the back of the lay and having another arm extending down along the front of the lay and having the upper part thereof spaced from the beam, and beads on the lay resiliently engaged by said arms to hold the clip and cover plate in position on the beam.

7. In a narrow ware lay beam having a reed at the rear thereof and a shuttle block on each side

of the reed, the beam having a rack rod in a slot extending under the shuttle blocks, a cover plate on the lay beam between the shuttle blocks extending over said slot, a resilient clip extending over the cover plate having a rear depending arm extending down along the back of the beam and terminating above the bottom of the reed, the cover plate having a front depending resilient arm extending down along the front of the beam, and lengthwise beads on the beam under which 10 said arms extend to hold the clip and cover plate on the beam.
